(57) **CLAIM**

The ornamental design for a laser level attachment, as shown and described.

DESCRIPTION

FIG. 1 is an isometric view of the laser level attachment, showing my new design;

FIG. 2 is a front plan view thereof;

FIG. 3 is a rear plan view thereof;

FIG. 4 is a left side plan view thereof;

FIG. 5 is a right side plan view thereof;

FIG. 6 is a top plan view thereof;

FIG. 7 is a bottom plan view thereof;

FIG. 8 is an isometric plan view of the laser level attachment from the bottom side; and,

FIG. 9 is a cross-sectional plan view of the laser level attachment taken along line 9-9 of FIG. 6.
